UNITED STATES PATENT OFFICE.

ABEL ROSE, OF CLEVELAND, OHIO.

TROUSERS SUPPORT.

1,423,684.

Specification of Letters Patent. Patented July 25, 1922.

Application filed February 4, 1921. Serial No. 442,420.

To all whom it may concern:

Be it known that I, ABEL ROSE, a citizen of the United States, residing at Cleveland, in the county of Cuyahoga and State of Ohio, have invented certain new and useful Improvements in Trouser Supports, of which the following is a specification.

My invention relates to improvements in trousers supports, and more particularly to 10 that type or class which are adapted to be secured about the waist of the wearer and are provided with suitable attaching devices adapted to receive and support suitable trousers supporting and attaching devices 15 arranged within the upper marginal edges or waist portion of the trousers.

My invention further relates to a combined abdominal and trousers supporting belt made in two side sections, the side sections being particularly designed and adapted to afford ease and comfort in wearing and to be readily adjusted to conform to the body of the wearer, said side sections being 20 adjustably and resiliently connected at their rear and being preferably arranged with the upper and lower edges diverging to form suitable abdominal supporting pads or sections at the front and being provided with suitable attaching devices for connecting 25 and disconnecting.

The invention further relates to improved clasp or fastening devices for facilitating the attachment and detachment of the belt sections with respect to the upper edges or 30 waistband section of the trousers.

With the above mentioned and other ends in view, the invention consists in the novel construction, arrangement and combination of parts, hereinafter described, illustrated 40 in some of its embodiments in the accompanying drawings and particularly pointed out in the appended claims.

Fig. 1 is a perspective view of a supporting belt constructed in accordance with this 45 invention. Fig. 2, a fragmentary perspective view of the inner upper or waist band portion of a pair of trousers equipped with detachable fastening devices adapted to be attached to the supporting belt. Fig. 3, a 50 fragmentary detailed view of the detachable and adjustable yielding connections at the rear of the supporting belt.

Figs. 4, 5, 6, and 7, are detail views of the 55 form of inner trousers fasteners shown in Fig. 2. Figs. 8 and 9 are, respectively, front and edge views of the belt carried fastener

loops shown on the outer sides of the supporting belt in Fig. 1. Fig. 10, a perspective view of a modified form of supporting belt. Fig. 11, a perspective view of a modified form of fastener or clasp applied to the upper edges of the trousers and supporting belt. Figs. 12 to 16 are detail views of the clasp.

Similar numerals of reference designate 65 like parts throughout all the figures of the drawings.

The improved support preferably comprises a two-part supporting belt consisting 70 of side sections 1, arranged to be connected at the front and back.

The sections 1, of the belt, are preferably 75 adjustably and yieldingly connected at the rear by means of elastic straps 2, adapted to be connected and adjusted by means of suitable adjusting and fastening devices 2^a. As a means of detachably connecting the side sections 1, at the front, a suitable fastening device 3, is provided, said fastening device, in the present instance, comprising a body 80 member 3, and a pivoted hook member 3^a, of a well known and understood construction, said hook member 3^a, being adapted to extend through an opening in an attaching plate 3^b, on the adjacent belt section. 85

As a means of attaching the belt to the inner upper or waist portion of the trousers, suitable fastening devices 4, are provided about the outer sides of the belt, said devices 4, in the present instance, being in the 90 form of horizontally extending metal loop members, said loop members being preferably spaced about the outer sides of the belt to correspond with the usual buttons on the trousers and being preferably spaced slightly 95 below the upper marginal edge thereof so as to be concealed by the upper marginal edges of the trousers when the latter are attached.

As a means of attaching the trousers to 100 the fastening devices 4, of the belt sections, any suitable and convenient fastening devices may be employed, said fastening devices being either in the form of clasps 5, as shown in Fig. 11, of the drawings, or in the 105 form of internally arranged fastener plates 6, as shown in Fig. 2, of the drawings. In either instance the clasps are provided with depending tongues 5^a, and 6^a, adapted to extend beneath and be seated within the fastening loops 4, on the outer sides of the belt sections. 110

In the form shown in Fig. 11, of the drawings, the main body portion of the clasp is provided with a struck-out tongue 5^a, adapted to extend through a similar shaped opening in the pivoted member 5^c, the members 5 and 5^c, being provided with jaws 5^a, adapted to engage with the inner and outer portions of the upper or waist band portion of the trousers, and the tongue being adapted 10 to be secured in position by the pivoted member 5^c.

In the form shown in Fig. 2, of the drawings, the fastener plate 6, is provided with slidably mounted spaced pin members 6^b, 15 which are adapted to pass through the goods on the inner sides of the trousers, the free ends of the pins 6, being secured in the protecting keeper plate 6^c.

As a means of adapting the improved belt 20 as an abdominal support, the front upper and lower edges 1^a, and 1^b, respectively, preferably diverge from each other forming a relatively wide abdominal supporting section 1^c, as shown, said sections being suitably 25 spaced apart as shown. The supporting sections 1^c, are preferably connected by single fastening devices arranged substantially midway between the upper and lower edges thereof, and in some instances the abdominal 30 supporting sections 1^c, will be provided with inclined portions 1^d, as shown in Fig. 1, of the drawings.

The belt sections 1, are preferably provided at suitable intervals with vertically extending stays 1^e, which serve to appropriately stiffen the belt sections and keep the parts in place.

Having thus described some of the embodiments of my invention, what I claim and desire to secure by Letters Patent, is,— 40

1. In a trousers support, the combination with a pair of trousers provided with a waistband, and a series of attaching devices extending along and detachably connected to the marginal edges of said waistband and 45 provided with depending hooks; of a trousers supporting belt comprising two side sections adapted to be arranged within said waistband and provided on their outer portions with loops adapted to receive the hooks 50 of said fastening devices.

2. In a trousers support, the combination with the waistband portion of a pair of trousers having detachable attaching devices detachably connected to the waistband and 55 provided with depending hooks arranged within and protected by said waistband; of a trousers supporting belt comprising two side sections arranged within said waistband and receiving the hooks of said fastening 60 devices.

In testimony whereof I have affixed my signature.

ABEL ROSE.
